UNITED STATES PATENT OFFICE.

GEORGE L. SMITH, OF FORT WAYNE, INDIANA, ASSIGNOR TO THE SMITH CHIMES CLOCK COMPANY, A CORPORATION OF INDIANA.

GONG-STRIKING APPARATUS.

Application filed January 6, 1923. Serial No. 610,985.

To all whom it may concern:

Be it known that I, GEORGE L. SMITH, a citizen of the United States of America, and resident of Fort Wayne, in the county 5 of Allen and State of Indiana, have invented certain new and useful Improvements in Gong-Striking Apparatus, of which the following is a specification.

This invention relates to improvements 10 in gong striking apparatus, and the object thereof is to provide a mechanism so constructed as to effect the striking of a gong a predetermined number of times upon a single manual operation. The invention is 15 intended particularly for use as an adjunct to ceremonials, and the like, where a series of musical sounds constitute a significant part. This object is accomplished by the construction illustrated in the accompanying 20 drawings in which:—

Fig. 1 is a front elevation showing the general arrangement of parts, a portion being broken away;

Fig. 2 is a front elevation of the striking mechanism upon an enlarged scale;

Fig. 3 is a side elevation projected from Fig. 2;

Fig. 4 is a detail view showing the rear elevation of the winding drum and other parts co-operable therewith; and

Fig. 5 is a detail view of the ratchet mechanism for the winding shaft.

The characters appearing in the description refer to parts shown in the drawings 25 and designated thereon by corresponding characters.

The invention consists of a case 1, the front of which is closed by a transparency 2 which is intended to be illuminated from 30 electric lamps 3 mounted within the case. A gong 4 is suspended in the case in position to be struck by a hammer 5 that forms part of a striking mechanism 6. The shank of the hammer consists of a spring bar 7 which is rigidly secured at one end to a bracket 8. A buffer 9 is positioned in the 35 case and contacts with the spring bar as the hammer strikes the gong, the purpose of the buffer being to prevent the hammer 50 from rebounding against the gong.

The striking mechanism includes a train 55 of gears 10 mounted in a frame 11, a winding-shaft 12 and fly-shaft 13 having operative relation with the train of gears as in the usual form of clock work. On the

fly-shaft is a dog 14 and also a governor fan 15. The largest gear 16 of the train is mounted loosely on the winding-shaft and has an annular series of pins 17, also in fixed connection with the gear 16 is 60 a cam-wheel 18 in the outer perimeter of which is a recess 19. The cam-wheel is secured to the gear by means of studs 20. Upon the winding-shaft is a fixed ratchet-wheel 21, and upon the gear 16 is a pawl 65 22 that engages the ratchet-wheel so that when the winding-shaft is turned in one direction movement will be imparted to the gear.

A coil spring 23 secured in the frame has 70 connection with the winding-shaft 12 by which it is wound, and upon the winding shaft is fixedly mounted a drum 24 having coiled thereon a pull-string 25 by which the drum is manually rotated. A stud 26 75 extends through the drum in a line parallel with the axis thereof with its ends projecting from the corresponding ends of the drum. A swinging stop 27 is pivotally supported on the frame and has a pendent 80 finger 28 and shoulder 29 at its lower end. Said finger rests against the projecting stud 26 so that the stop is held in its outward position while the opposite end of the stud 26 is engaged in the hooked lower end of 85 a trigger 30 that extends from a rocker-shaft 31 which is mounted in the frame. The rocker-shaft has fixed thereon a finger 32 that is positioned so as to engage the dog 14 and interrupt rotation thereof when the trigger 30 has hooked engagement on the stud 26. The rocker-shaft 31 has also fixed thereon a drag-member 33 having a pendent end that extends into the recess 19 of 90 the cam-wheel 18 so as to permit the rocker-shaft to turn sufficiently to move the finger 32 into engagement with said dog. A lever 34 is pivotally supported in the frame with one of its ends extending into the path of the pins 17 on the gear so that the lever is 95 oscillated by engagement therewith. The opposite end of said lever has connection with the shank 7 of the hammer by means of a flexible cord 34' so that as the lever is actuated the hammer will accordingly be 100 actuated and the gong sounded. A buffer 35 on the frame confines the movement of the lever within the range of the pins by 105 which it is actuated.

It is the intention that the sounding of 110

the gong and the illumination of the transparency shall be concurrent, and in order to effect the illumination of the transparency during the operation of the striking mechanism, a flasher 36 is arranged in operative connection with the gear 16 of the striking mechanism and connected in circuit with one of the electrical conductors 37, with which the various lamps 3 are connected and with which they are supplied with current. The flasher may be of any suitable construction, such as is common in the art, which will have the effect of periodically closing the electrical circuit that supplies the lamp with current. In the present instance the flasher consists of a contact drum 38 having a gap 39 and mounted so as to be rotated upon a shaft 40, and a pair of brushes 41 that contact with the drum, except during the passage of the gap, as the drum is rotated, the brushes being connected in circuit with the conductors 37 in the usual manner. Upon the shaft 40 is mounted a gear 42 that meshes with the gear 16 so as to be rotated thereby, which has the effect of actuating the drum accordingly.

In operating the invention, the pull-string is manually drawn downwardly and the winding drum is thus revolved until the stud 26 comes into contact with the shoulder 29 on the stop 28. When the stud reaches the stop, it also raises the trigger 30 by coming into contact with the lower face of its hooked end. As the trigger is raised, the finger 32 is thereby swung out of range of the dog 14, and the drag member 33 is withdrawn from the recess 19 in the cam-wheel. Also, the spring 23 is wound up. When the pull-string is released, the shaft is returned to its former position by the action of the spring, causing the gear 16 and the drum 24 to react with it. As said gear revolves, the pins 17 in successive order trip the lever 34 causing the hammer to be actuated until the move-

ment of the drum 24 is stopped by engagement of the stud 26 in the hooked end of the trigger 30. During the revolution of the gear 16 the drag member is held in an elevated position upon the perimeter of the cam-wheel 18, which has the effect of withholding the finger 32 from interference with the dog 14 on the fly-shaft until the drag member drops into the recess 19 in the cam-wheel at the completion of its revolution.

The apparatus thus constructed, provides for the automatic striking of the gong a predetermined number of times according to the number of pins in the series of pins set in the gear 16, and the simultaneous illumination of the transparency, by the simple manual operation of a downward pull of the pull-string.

What I claim is:

1. Apparatus comprising a case; a gong suspended in the case; a hammer for striking the gong; a mechanism for actuating the hammer; a spring having actuating relation with said mechanism; and a winding drum having a pull-string wound thereon and having limited actuating relation with said spring and controlling relation with said mechanism.

2. In combination with a gong and a hammer for striking it, a mechanism including an oscillating lever actuated thereby; a flexible connection between the said lever and the hammer; a spring having actuating relation with said mechanism; and a manually operated winding means having actuating relation with the spring and controlling relation with said mechanism.

In testimony whereof I affix my signature in presence of two witnesses:

GEO. L. SMITH.
